Patented Dec. 30, 1969

216,410

COMBINED CHAFING DISH AND SUPPORT TRAY THEREFOR

Alberto Porciani, Via di Montebuono,
Barile, Pistoia, Italy

Filed Sept. 20, 1968, Ser. No. 13,636

Claims priority, application Italy Mar. 22, 1968

Term of patent 14 years

Int. Cl. D7—02

U.S. Cl. D44—15

FIG. 1

FIG. 2

In the drawing:

FIG. 1 is a front perspective view of a combined chafing dish and support tray therefor embodying my new invention;

FIG. 2 is a rear perspective view thereof.

I claim:

The ornamental design for a combined chafing dish and support tray therefor, substantially as shown.
